UNITED STATES PATENT OFFICE.

ALBERT F. BUTLER, OF SHARON, PENNSYLVANIA.

BOWLING-ALLEY.

1,302,897.

Specification of Letters Patent.

Patented May 6, 1919.

Application filed August 3, 1918. Serial No. 248,094.

To all whom it may concern:

Be it known that I, ALBERT F. BUTLER, a citizen of the United States, and resident of Sharon, in the county of Mercer and State 5 of Pennsylvania, have invented certain new and useful Improvements in Bowling-Alleys, of which the following is a specification.

This invention relates to new and useful 10 improvements in bowling alleys, and more particularly to those in use for playing ten pins and duck pins.

The object of the invention is to provide 15 a bowling alley provided with means whereby when the bowler slides or steps over the foul line in the act of throwing the ball, this fact will be indicated and a deflector in front of the pins will be thrown up so 20 as to discharge the balls into the trough, thereby preventing the pins from being knocked or bowled over and necessitating their resetting, the device also serving as a check against scoring when there is a foul.

With the above and other objects in view, 25 as will appear as the description proceeds, the invention comprises the various novel features of construction and arrangement of parts which will be more fully described herein and set forth with particularity in 30 the claims appended hereto.

Reference is had to the accompanying 35 drawings forming a part of this application, in which like reference characters indicate the corresponding parts throughout the several views, in which—

Figure 1 is a plan view of an alley constructed in accordance with the invention,

Fig. 2 is a vertical longitudinal section,

Fig. 3 is a vertical cross sectional view, 40 taken on line 3—3 of Fig. 1,

Fig. 4 is a perspective view of the deflector, and

Fig. 5 is a detail showing the cable pulling means.

Referring to the drawings in detail, the 45 numeral 10 designates the runway of an alley 11, along which the balls are thrown at the pins 12 adjacent to the pit 13. The troughs at either side are designated at 14 and the ball rack at 15. Suitable transverse joists 16 are provided in order to form a space beneath the flooring of the bowling alley, and supported adjacent to the foul line 17 is a compressible flooring part 18, the 50 edge thereof remote from the foul line 17 being hinged for downward movement as

shown at 19. Suitable means are arranged beneath the foul line flooring part 18, such as expandable coil springs 20, so as to hold said compressible part of the flooring in alignment with the remaining part, limited in its upward movement at the hinge connection and adjacent to the foul line. 60

Adjacent to the opposite end of the alley in front of the pins or pin stops is a V-shaped compressible flooring part 21, that is, such part comprises a strip extending rearwardly at each side, the strip being pivoted at its opposite edges, as shown at 22, and being held in alignment with the flooring by 65 suitable means consisting of expandable coil springs 23, in the form shown. The flooring part 21 is designed to be elevated instead of being depressed, when operated, and for this purpose there is arranged longitudinally beneath the flooring a cable 24 which passes beneath the flooring part 18 and is anchored as shown at 25 to one of the transverse joists 70 16 beneath the runway 10, and passes around a series of pulleys 26, the movable edge of 75 the flooring part 18 at the foul line being provided with a depending portion 27 designed to engage the cable for depressing the same and pulling upon the cable at the pit end thereof. 80

At the pit end of the cable adjacent to the deflector part of the flooring, shown at 21, the cable passes around pulleys 28, being bifurcated and extended to opposite sides of the alley beneath the deflector part 21 and 90 connected to the latter adjacent to its rear edges, so as to pull downwardly on the compressible rear portion 22, thereby elevating the forward edge, while the springs 23 serve to return the flooring to its original position. This action is also assisted by a plurality of springs, preferably two, 29 connected to one of the joists 16 in front of the deflector portion 21 and to the forward edge of the latter, as shown. 95

Thus, it will be seen that when a ball is thrown and the bowler steps over the foul line, the platform 18 will be depressed thereby elevating the deflector, so that when the ball strikes the deflector, it will be discharged 100 at either side of the alley without striking the pins and necessitating that the same be reset.

From the foregoing description taken in connection with the accompanying drawings, it is thought that a clear and comprehensive understanding of the construction, 110

operation, and advantages of my invention may be had, and while I have shown and described the device as embodying a specific structure, I desire that it be understood that 5 such changes may be made in said structure as do not depart from the spirit and scope of the invention as claimed.

Having thus described my invention, what I claim is new and desire to secure by Letters Patent, is:

1. A bowling alley having a depressible portion adjacent to the foul line, a deflector adjacent to the pin stops adapted to be elevated, and means to cause elevation of the 15 deflector upon stepping on the depressible portion.

2. In a bowling alley, a flooring having a runway, an alley portion including a pin setting part and a ball pit beyond the same 20 with stops on either side, a depressible flooring part beginning at the foul line of the alley, a deflector in front of the pin stops, and connection between the depressible part and the deflector for elevating the latter 25 upon depressing the flooring part.

3. In a bowling alley, a flooring having a runway, an alley portion including a pin setting part and a ball pit beyond the same with stops on either side, a depressible flooring part beginning at the foul line of the 30 alley, a deflector in front of the pin stops, means for holding said depressible part of the flooring in alinement with the remaining

part, means for holding the deflector part of the flooring in alinement with the remaining 35 part of the flooring, said deflector being substantially of V-form and sloping at either side toward the ball pit, and cable connections between the depressible part of the flooring and the deflector for elevating the 40 latter upon depressing the flooring adjacent to the foul line.

4. In a bowling alley, a flooring having a runway, an alley portion including a pin setting part and a ball pit beyond the same 45 with stops on either side, a depressible flooring part beginning at the foul line of the alley, a deflector in front of the pin stops, means for holding said depressible part of the flooring in alinement with the remaining part, means for holding the deflector part of the flooring in alinement with the remaining part of the flooring, said deflector being substantially of V-form and sloping at 50 either side toward the ball pit, springs connected to the deflector and to the depressible portion to return the same to alinement with the flooring, a cable beneath the depressible part of the flooring and connected to the rear portion of the deflector part whereby to elevate the latter when the depressible part is moved downwardly to exert pull on the cable. 55

In testimony whereof I affix my signature hereto.

ALBERT F. BUTLER.
